UNITED STATES PATENT OFFICE.

DION GERALDINE, OF CHICAGO, ILLINOIS.

MECHANICAL MASSAGING APPARATUS.

1,161,767.

Specification of Letters Patent. Patented Nov. 23, 1915.

Application filed December 14, 1914. Serial No. 877,012.

To all whom it may concern:

Be it known that I, DION GERALDINE, a citizen of the United States, and a resident of Chicago, in the county of Cook and State of Illinois, have invented certain new and useful Improvements in Mechanical Massaging Apparatus; and I do hereby declare that the following is a full, clear, and exact description thereof, reference being had 10 to the accompanying drawings, and to the characters of reference marked thereon, which form a part of this specification.

This invention relates to a novel mechanical massaging machine for massaging the 15 trunk and lower limbs of the human body, and the invention consists in the matters hereinafter set forth and more particularly pointed out in the appended claims.

One of the objects of the invention is to 20 simplify and reduce the cost of mechanical massaging machines or apparatus, their weight and the space required to contain them.

A further object of the invention is to 25 improve the efficiency of such mechanical massaging machines, and to this end the invention comprises as one of its features a plurality of independently adaptable applicators, so assembled and arranged that each 30 individual applicator, when passing over the body, is free to adapt itself to the contour of the body in close simulation of the operation of the human hand.

A further object of the invention is to 35 provide, in an apparatus of this character, means for adjusting the series of applicators so as to adapt the same to patients of widely diverging sizes.

A further object of the invention is to 40 provide means for yieldingly pressing the independently adaptable applicators against the body, and for adjusting the range of pressure.

Another object of the invention is to 45 provide means for quickly opening and closing the circular series of applicators to permit the patient to readily step into and out of the machine and to quickly adjust the applicators to the body.

Another object of the invention is to 50 provide means for automatically raising and lowering the series of applicators and reversing the direction of motion thereof at the ends of the throw or movement.

A further object of the invention is to 55 provide means whereby the speed of travel of the applicators along and over the body may be varied.

Another object of the invention is to provide a machine the movements of which may 60 be readily controlled by the patient, thereby avoiding the necessity of a supervising attendant.

In the drawings: Figure 1 is a side elevation of a mechanical massaging machine embodying my invention. Fig. 2 is a plan view thereof. Fig. 3 is a detail showing one form of reversing mechanism for reversing the direction of motion of the circular series of applicators. Fig. 4 is an axial 70 sectional detail of a pulley, showing one method of adjusting the rate of speed of the applicators. Figs. 5, 6, 7 and 8 are details of the applicators and the arms which carry the same, showing also the means for 75 pressing the applicators toward and against the body. Fig. 9 is a detail showing a portion of the annular applicator supporting frame. Figs. 10 and 11 are details showing one means of adjusting the size of the annular series of applicators, and for varying 80 the pressure by which the applicators are pressed against the body. Fig. 12 illustrates the manner in which the applicators are pressed against the body of the patient. 85 Figs. 13 and 14 are details of a modification. Figs. 15, 16 and 17 are details of a further modification.

The machine herein shown as illustrative of one embodiment of my invention embraces, in general terms, an upright support or standard, a circular series of applicators and a frame therefor into which the patient is adapted to step so that the series of applicators encircle the patient, means for adjusting the applicators to and pressing them against the body of the patient, with means for supporting the series of applicators on said standard and for moving it up and down thereon to cause the 100 applicators to travel along and against the body.

Referring now to the specific structure shown in the drawings, 10 designates the base of the machine; 11 a vertical standard 105 attached to the base and rising therefrom which, in practice, is preferably tubular; 12 a carriage which is movable vertically on

said standard through the medium of bearing rollers 13, 13; and 14 an annular or ring-like frame which is supported from said standard through the medium of arms 15, 15 and upper and lower braces 16 and 17, respectively. The said frame comprises an outer member 18 consisting preferably of flat band metal with rounded edges, and an inner curved member 19 which is preferably 10 cylindrical in cross section and is supported on the band 18 by means of lugs or loops 20. 22 designates an annular series of applicators which consists, preferably, of wood rollers having crowned faces or peripheries. 15 The said applicators, as herein shown, are arranged in upper and lower pairs, with the upper pair slightly off-set from the lower pair, in the manner shown in Figs. 7 and 8. The said rollers are rotatively mounted on 20 shafts 24, 24 which are carried by arms 25 of blocks or carriers 26 that are pivoted between their ends at 27 to the upper ends of radially swinging arms 28. The arms are provided at their lower ends with pivot 25 eyes 29 which fit over the cylindric or rod-like member 19 of the applicator frame 14, whereby said arms are pivoted to the frame to permit the upper ends thereof to swing radially inwardly and outwardly, to shift 30 toward and from the body of the patient. The said applicator carrying arms are placed under the influence of coiled springs 30 which, as herein shown, are coiled about the frame member 19 and bear at their free 35 ends against the frame member 18 and the arms in such manner as to tend to throw the upper ends of the arms and the applicators carried thereby outwardly or away from the patient. Thus, when the arms are 40 unrestrained the springs 30 serve to automatically open the series of applicators and to hold them open in the manner shown in Figs. 1 and 2.

One of the features of my invention reside 45 in providing means for pressing or forcing the applicators toward the body of the patient in such manner that each applicator unit, consisting of the two pairs of rollers referred to, is separately adaptable to the 50 body of the patient and, at the same time, to provide means whereby the pressure by which the applicators are forced against the body may be varied.

As shown in Figs. 1, 2 and 5 to 11, inclusive, the means for so adapting the applicators to this, what may be termed, independent action, consists in providing an elastic tape or web 35 which is adapted to pass through loops 36 in the applicator 55 blocks 26, said loops being preferably provided at their inner sides with rollers 37 about which the web is trained, whereby the web is free to pass through the loops. The ends 38, 38 of the said elastic web are 60 brought together at one side of the series of

applicators and are attached to and adapted to be wound upon a reel or drum 39 (Figs. 6, 10 and 11) which is rotatively mounted in a lateral extension 40 which is made part of or carried by one of the applicator blocks 26. The said web ends are carried to said reel 39 around guide pulleys 41 rotatively mounted in the extension 40. The reel is provided with a hand wheel 42 by which it may be turned to wind the web 75 thereon and to thereby constrict the diameter of the web and the annular series of applicators controlled thereby. The reel is locked from rotation and the web held in a given adjustment by means of a spring 80 pressed pawl 44 (Figs. 6 and 10) carried by the extension 40 and which engages the teeth of a ratchet 45 fixed to the reel shaft. With this construction it will be evident that by turning the reel the diameter of the annular series of applicators is reduced to correspond with the size of the body of the patient and also to vary, at will, the pressure by which the applicators are to be pressed 85 against the body. When the pawl 44 is released from the ratchet, the springs 30 act, through the radially swingable arms 28, to swing the upper ends of said arms and the applicators outwardly.

As shown in Figs. 1 and 2, the series of 90 applicators are expanded to the extreme diameter of the series. In Fig. 12 they are shown as contracted to contact with the body of the patient. When the said applicators are adjusted to the body they may be 95 arranged so as to be brought practically together at their sides to constitute a full unbroken circle of applicator surface, or it may be desirable in some instances to have the applicators angularly spaced when applied to the body of the patient. In order to adapt the machine to persons of different size, and, at the same time, produce a practically continuous applicator surface, as indicated in Fig. 12, I may provide each machine with two or more sets of rollers of different lengths to be applied to the shafts 24 or may arrange each machine so as to receive a greater or less number of applicator 100 carrying arms 28.

Another feature of my invention resides in the arrangement of the applicators so as to follow the contour of the body in close simulation of the hands of an operator thereon. This effect is produced, in the 105 construction herein shown, by pivoting the blocks 26 at or about their centers, so that when they are pressed toward and against the body by means of the elastic web 35 referred to, or by other equivalent means to be 110 hereinafter described, the blocks 26 are free to swing vertically on their pivots and thereby permit the upper pair of rollers to swing inwardly relatively to the lower pair and vice versa, and thus adjust the upper and 115 lower pairs of rollers to follow the contour of the body.

lower pairs in their vertical movement to uneven and irregular contours of the body. By reason of the separate mounting of each set of rollers and of the means for pressing them inwardly against the body, each set is further separately adaptable to irregularities in the circumference of the body.

- Referring now to the means for raising and lowering the applicator frame 14 so as to cause the applicators to travel up and down the body, the same is herein shown as made as follows: 50 designates a drum which is mounted on a horizontal countershaft 51 that is rotatively mounted in standards 52, 52 which are attached to and extend upwardly from the base 10. 53 designates a cable which is wound between its ends a number of turns upon said drum. One end of said cable is trained downwardly from the drum over a pulley 55, shown in dotted lines in Fig. 1, and thence carried upwardly and is attached to the carriage 12 at 56. The other end of the said cable is carried upwardly over pulleys 57, 57 at the top of the standard 11, and is thence carried downwardly and is attached at 58 to the upper end of the carriage 12. The applicator frame and the applicators carried thereby are counterbalanced by a weight 59, shown in dotted lines in Fig. 1, and contained within the tubular standard 11, which weight is connected by a cable 60, that extends upwardly from the weight through the hollow standard and is trained over one of the pulleys 57 and extends downwardly therefrom for attachment to the applicator frame at 62. The countershaft 51 is driven from a motor 65 supported on the base 10 through a suitable speed reducing gear 66. The terminal shaft 67 of the said speed reducing gear is provided with a beveled pinion 68 which meshes with two opposed beveled pinions 69, 70, respectively, that are normally loose on the countershaft. 71 designates a sliding clutch ring or sleeve which is splined to the countershaft and is provided at its ends with teeth adapted to engage into teeth on the adjacent inner sides of the beveled pinions 69, 70, the parts being so arranged that when said clutch sleeve is in its neutral position, both pinions 69, 70 rotate freely on the countershaft 51, and when said sleeve is shifted to one or other of its limits of movement it locks one of said pinions 69 and 70 to rotate with the clutch sleeve so as to thereby drive the countershaft in one direction or the other, depending upon which of the pinions is so locked. With this construction, the countershaft may be rotated in either direction to raise and lower the applicator frame at will. Any suitable means may be employed for reversing the direction of rotation of the countershaft and for thereby reversing the direction of movement of the applicator

frame. As herein shown, I have provided an L-shaped shifted lever 73 which is pivoted at its angle at 74, with the short arm thereof loosely connected to the clutch sleeve. The longer arm of the lever 73 extends horizontally over the drum 50 and is forked to provide a slot through which the cable 53 passes. The said cable 53 is provided at two points in its length with enlargements 75, 76 which are of such size as to readily pass about the drum, but are made slightly larger than the slot in the clutch shifter lever so that as the cable travels through said slot in one or the other direction one of the enlargements engages the lever and actuates it to shift the clutch sleeve and thereby change the direction of rotation of the countershaft 51 and the direction of movement of the applicator frame. The said enlargements 75, 76 may be clamped upon the cable in any suitable manner by means permitting them to be shifted lengthwise of the cable so as to thereby vary the length of travel or throw of the carriage 12. One means of varying the speed at which the carriage and the applicator frame travels is illustrated in Fig. 4, wherein it is shown that the drum 50 comprises a series of concentric cylindric shells 80, 80 which are confined between the opposed tapered faces of cones 81, 81, that are sleeved over the countershaft 51 and are attached thereto in any suitable manner. With this construction, the diameter of the drum may be varied by removing or replacing one of the shells 80 and winding the cable on the retained exterior retained shell, or vice versa.

In Figs. 13 and 14, is shown a modified means of supporting the applicator rollers. As shown in said figures the applicator rollers 84, 84 are made generally similar to the rollers hereinbefore described and are supported by an inflatable and deflatable hollow flexible ring member 85 which is backed by a metal ring 86 which, in a general way, takes the place of the open or ring-like frame 14, before described. The rollers 84, which are arranged in pairs, are mounted on axles carried by brackets 87 which extend inwardly from bases 88 that are secured in any suitable manner to leather or like facing straps 90, which are carried by the inflatable ring member 85 of the applicator frame. The said straps 90 are strapped about the frame through the medium of take-up buckles 91 connected to the terminals of the leather or like facing straps and, preferably, the buckles and one of the terminals of each strap are connected by a spring 92. As herein shown, I have arranged the applicators in groups of three pairs, said pairs being staggered or arranged in offset relation to each other and adapted to be arranged closely adjacent to an adjoining group to provide a substan-

tially continuous applicator surface. In this construction, the diameter of the applicator carrying frame may be varied by inflating the ring member 85 more or less.

5 In Figs. 15, 16 and 17, I have shown another modification of the means for carrying the applicator units. As therein shown, the applicator rollers 95 are mounted on carriers 96 which are pivoted centrally 10 thereof at 97 to the inner ends of bow springs 98. The outer ends of said bow springs extend outwardly over the ring like applicator supporting frame 99 and are pivoted at 100 to the lower margin of said 15 frame. One edge of the bow springs 98 is adapted to be engaged by a notched locking pawl 101 which is hinged at 102 to the frame 98 and is pressed by a spring 103 against the adjacent side of the associated bow spring 20 to thereby lock the spring in any position desired. The said locking device and the pivotal connection of the bow spring with the open frame 98 constitutes means for varying the diameter of the series of applicator units and for locking the series in any 25 given adjustment desired.

While I have described with some detail a preferred embodiment of my invention and modifications thereof, it is to be understood 30 that the invention is not thereby limited in its scope except as to such claims wherein structural details are specifically claimed, and as imposed by the prior art.

I claim as my invention:

35 1. A mechanical massaging apparatus embracing an encircling series of independently adaptable applicator units, with a common interconnecting means acting to press the units against an encircled body.

40 2. A mechanical massaging apparatus embracing an encircling series of interconnected, independently adaptable applicator units embracing tiltable upper and lower applicator members with adjustable pressure means to press the applicator members 45 against the body.

3. A mechanical massaging apparatus embracing an encircling series of tiltable independently and automatically adaptable 50 applicator units with means for raising and lowering said series, whereby the applicators may travel along the body and limbs of the patient.

4. A mechanical massaging apparatus embracing an encircling series of applicator units, with a mounting therefor constructed to permit independent radial and tilting motion of said units, means for raising and lowering said series, and reversing means 60 operable at the limits of movement of said series to reverse the direction of movement thereof.

5. A mechanical massaging apparatus embracing an encircling series of applicator

units, with a mounting therefor constructed 65 to permit independent radial and tilting motion of said units, means for raising and lowering said series, reversing means operable at the limits of movement of the said series to reverse the direction of movement 70 thereof, and means associated with the raising and lowering means to vary the rate of travel of said series.

6. A mechanical massaging apparatus comprising an open frame, supporting 75 means therefor arranged to permit vertical movement of the frame, a circular series of interconnected independently and automatically adaptable applicator units and supports therefor carried by said frame and 80 movable radially toward and from the center of the frame, on which said units are pivotally carried, with means whereby said units are movable toward and from the center of the said series. 85

7. A mechanical massaging apparatus comprising an open frame, supporting means therefor arranged to permit vertical movement of the frame, a circular series of applicator units, and carrying members 90 therefor supported on the frame and freely movable radially toward and from the center of the series to automatically adapt them to the contour of an encircled body.

8. A mechanical massaging apparatus 95 comprising an open frame, supporting means therefor arranged to permit vertical movement of the frame, a circular series of applicator units, carrying members therefor supported on said frame, means acting on the 100 units to yieldingly press them against a body encircled thereby, and means acting on the carrying members to move the applicator units when unrestrained, outwardly.

9. A mechanical massaging apparatus 105 comprising an open frame, supporting means therefor arranged to permit vertical movement of the frame, arms pivoted at their lower ends to said frame to swing at their upper ends inwardly and outwardly, 110 applicator units pivoted to the upper ends of said arms, with means for yieldingly pressing said units toward a body encircled thereby.

10. A mechanical massaging apparatus 115 comprising an open frame, supporting means therefor arranged to permit vertical movement of the frame, arms pivoted at their lower ends to said frame to swing at their upper ends inwardly and outwardly, 120 applicator units pivoted to the upper ends of said arms, with means for yieldingly pressing said units toward a body encircled thereby, and springs acting on said arms to swing them outwardly when said pressing 125 means are released.

11. A mechanical massaging machine comprising a circular series of independently

adaptable applicator units and an elastic web for connecting said units and for pressing them radially inwardly.

12. A mechanical massaging apparatus comprising a circular series of independently adaptable applicator units, an elastic web for connecting said units and for pressing them radially inwardly and adjusting means acting on the web for varying the 10 diameter of said series.

13. A mechanical massaging apparatus comprising a circular series of independently adaptable applicator units, an elastic web for connecting said units and pressing them radially inwardly, a reel carried by one of said units to which the ends 15 of said web are attached, and releasable locking means for locking the reel from rotation.

20 14. A mechanical massaging apparatus comprising an open frame with means to support it permitting the frame to rise and fall, arms hinged to said frame, applicator units carried by said arms and an elastic 25 web connecting said units, with means for varying the diameter of the series of applicator units carried by said arms.

15. A mechanical massaging apparatus comprising an open frame, with means to 30 support it permitting the frame to rise and fall, arms hinged to said frame, applicator units carried by said arms, an elastic web connecting said units, a reel carried by one of the said units about which the ends of 35 said web are adapted to be wound, and pawl and ratchet mechanism for locking said reel from rotation.

16. A mechanical massaging apparatus comprising an open frame, with means to 40 support it permitting the frame to rise and fall, a circular series of applicator units, with means to press them against a body encircled thereby and supporting members therefor carried by said frame, each of said 45 units comprising a carrier pivoted to its supporting member and applicator rollers mounted in said carrier.

17. A mechanical massaging apparatus comprising an open frame, with means to 50 support it permitting the frame to rise and fall, supporting members carried by said frame and movable radially toward and from the frame, slotted carriers pivoted to said members, applicator rollers mounted on 55 said carriers and an elastic web trained through slots in said carriers with means to vary the diameter thereof, for the purpose set forth.

18. A mechanical massaging apparatus 60 comprising an open frame, with means to support it permitting the frame to rise and fall, supporting members carried by said frame and movable radially toward and from the frame, slotted carriers pivoted to

said members, applicator rollers mounted in 65 said carriers, an elastic web trained through the slots in said carriers with means to vary the diameter thereof, and antifriction rollers mounted in said carriers at said slots for engagement by said web.

19. A mechanical massaging apparatus comprising an open frame, with means to support it permitting the frame to rise and fall, supporting arms hinged at their lower 70 ends to said frame, carriers pivoted between their ends to the upper ends of said arms, applicator rollers mounted on the ends of said carriers and means acting on the carriers to press the rollers against a body encircled by said rollers.

20. A mechanical massaging apparatus comprising an open frame, with means to support it permitting the frame to rise and fall, supporting arms hinged at their lower 75 ends to said frame, carriers pivoted between their ends to the upper ends of said arms, applicator rollers mounted on the ends of said carriers and means acting on the carriers to press the rollers against the body encircled by said rollers, the rollers of each 80 unit being arranged in pairs, with the upper pair of each unit out of line with the lower pair thereof.

21. In a massaging apparatus, a support 85 mounted to be movable toward and from the patient with means to yieldingly press it toward the patient, a carrier pivoted between its ends to said support and applicator member carried by the ends of said carrier.

22. In a massaging apparatus, an open 90 frame, a series of tilttable carriers supported thereby, with applicator members mounted on the ends of said carriers, and means acting on all of said carriers to press them toward an encircled body while permitting the carriers to tilt to permit the applicator members thereof to be adapted to the contour of the body.

23. In a massaging apparatus a radially 95 swinging arm, a carrier pivoted between its ends thereto and applicator rollers carried by the upper and lower ends of said carrier.

24. In a massaging apparatus a radially 100 swinging arm, a carrier pivoted between its ends thereto and applicator rollers carried by the upper and lower ends of said carrier, the upper roller being out of line with the lower roller, for the purpose set forth.

25. In a massaging apparatus, a series of 105 encircling applicator units, each unit being independently movable toward the axis of the series and each unit comprising a centrally pivoted carrier, with applicator rollers mounted in the ends thereof.

26. A mechanical massaging apparatus 110 comprising a base, a standard rising therefrom, a series of encircling, independently

2
tiltable applicators with means for independently and automatically adapting them to a body encircled thereby, a supporting frame for the applicators, and a carriage traveling on said standard for sustaining said frame.

27. A mechanical massaging apparatus comprising a base, a standard rising therefrom, a series of encircling tiltable applicators, with means for independently and automatically adapting them to a body encircled thereby, a supporting frame for the applicators, a carriage traveling on said standard for sustaining the frame, motor

driven means for raising and lowering said frame, and automatic means for reversing the motor driven means at the limits of movement of the applicator supporting frame.

In testimony, that I claim the foregoing 20 as my invention I affix my signature in the presence of two witnesses, this 8th day of December, A. D. 1914.

DION GERALDINE.
